DESIGN FOR A NASAL MASK

Walter M. Boothby, Arthur H. Bulbulian, and
William R. Lovelace, Rochester, Minn.

Application July 28, 1939, Serial No. 86,284

Term of patent 14 years

To all whom it may concern:

Be it known that we, Walter M. Boothby, Arthur H. Bulbulian, and William R. Lovelace, citizens of the United States, residing at Rochester, in the county of Olmsted and State of Minnesota, have invented a new, original, and ornamental Design for Nasal Mask, of which the following is a specification, reference being had to the accompanying drawing, forming part of the specification.

Fig. 1 is a front elevational view of a nasal mask embodying our new design;

Fig. 2 is a rear elevational view thereof; and
Fig. 3 is a side elevational view thereof.

We claim:

The ornamental design for a nasal mask, substantially as shown.

WALTER M. BOOTHBY.
ARTHUR H. BULBULIAN.
WILLIAM R. LOVELACE.
